UNITED STATES PATENT OFFICE.

JOHN HUBER, OF LOS ANGELES, CALIFORNIA.

FLANGING MACHINE.

Application filed July 24, 1924. Serial No. 727,874.

To all whom it may concern:

Be it known that I, JOHN HUBER, a citizen of the United States, residing at Los Angeles, in the county of Los Angeles and 5 State of California, have invented certain new and useful Improvements in Flanging Machines, of which the following is a specification.

My invention relates to the art of bending 10 sheet or plate metal, and consists of means for exerting holding pressure against the face of a plate during the flanging operation, as hereinafter described.

It has in view to utilize the main frame 15 and actuating mechanism of a power operated shear, punch, press, or other similar machine, by providing suitable die mechanism incorporated with the actuating plunger or head of the machine, together with a 20 suitable support for the plate or blank. Also, in combining with the main machine, and as a part of such supplemental equipment, a reciprocable pressing head or lever so mounted on the lower frame and connected 25 with the plunger as to be operated thereby, adapted to act upon the edge portion of the plate by a series of pressing or bending shoes or dies, while at the same time, exerting a correcting counter-acting or 30 flattening pressure during the bending or flanging operation.

The invention preferably utilizes a series of successively acting shoes or dies for the purpose of forming a flange or bend by a 35 corresponding series of successive operations, for rapidly forming the flange through such series of bending movements, like those shown and described in my prior application filed September 6, 1923, Serial 40 No. 661,243. The present application refers particularly to the construction of the pressing shoes secured to the under middle and side portions of the pressing head, for control of the plate during flanging.

45 In the drawings, illustrating the invention:

Figure 1 is a partial view in sectional elevation, showing the actuating mechanism mounted on and connected with the standard frame of a shear, punch, or press, at the completion of the flanging stroke;

Fig. 2 is a partial plan view of the pressing head;

Fig. 3 is a vertical section therethrough 50 on the line III—III of Fig. 2;

Fig. 4 is an edge view detached of the

middle pressing shoe of the pressing head;

Figs. 5, 6 and 7 are views in side and end elevation and plan respectively of the side pressing shoes of the pressing head. 60

In the drawings, 2 is the main frame or housing of a standard punch, shear, or press, having the usual anvil block or base 3, and head 4. Within the head is usually mounted a cam or eccentric-actuated plunger or base 5, to which may be attached the punch, shear, or die, commonly used in such machines. 65

In the present case, I substitute for such element a special head 38, adapted to interfit and firmly connect with the plunger 5 for intermittent downward and upward movement, as controlled by the usual clutch mechanism, as is well understood. For lifting the pressing head, a bracket extension 39 extends forwardly of head 38 carrying a bolt 40 connected with the pressing head 21. Said bolt extends through the bracket and is provided with a cushioning spring 41 for resiliently cushioning the weight of the 75 pressing head on upward movement.

Secured upon the upper face of anvil 3 is an anvil block 6 having its inner face downwardly and rearwardly inclined from the front at a suitable angle, and with an 80 inner face sufficiently deep to allow for the making of a flange of any desired depth.

The blank A, which is usually in the form of a circular plate or head, and which is to be peripherally flanged at substantially 90 right angles, is preferably laid across the upper portion of the anvil 6, as in Fig. 1, so that in the final pressing operation, shown in said figure, the terminal flange will be 95 bent down at substantially right angles to it when finished. Anvil 6, for such purpose, is provided with a removable face block or bearing shoe 7, held against the face of anvil 6 by bolts 8, as will be readily understood. 100

Shoe 7 is preferably rounded at its bearing corner 9 so as to provide an easy rounded joint for the flange, and such shoe is either laterally curved or straight as to its back face. If curved, the radius may be approximately that of the plate to be flanged, and the shoe is preferably made removable so as to allow of the substitution of different shoes.

For the purpose of supporting plate A, 110 I provide a frame 10 of structural shapes, properly braced, and having an inner sup-

porting bracket 11 which is pivotally mounted by a bolt 12 to the inner upper corner portion at each side of the anvil block 6. By such construction, the frame 10 may be raised or lowered, to adjust it to the desired position, and its outer end is supported by any suitable abutment 13 upon which the end of frame 10 rests.

A center supporting block 14 is secured by bolts 15 at any desired position longitudinally of frame 10, upon which it may be moved in or out to locate the block 14 at the desired distance outwardly from the anvil block 6. Block 14 is provided with a central stud 16 and nut 17, upon which the plate A may be pivotally secured for intermittent rotation during the successive flanging operations.

The upper face of the base 3 is so shaped or adapted as to provide a flat bearing for a base plate 18 of a hinged bearing block 19, adapted to receive the hinge pin 20 of pressing head 21. Said head, as shown, extends upwardly and outwardly over the anvil 6, having a middle pressing portion with an under flat face 22, either for initial pressing or for attachment against it of supplemental pressing dies or shoes. Beyond its middle portion, the pressing head 21 is widened, as indicated at 23, forming an elongated pressing base for the lower separately attached pressing shoes 24 and 38, 38, at the middle and each side or edge portion of the widened part 23 of pressing head 21, as shown. Block 24, which is generally triangular in cross section, is provided with a continuously flat inner face for engagement against the sloping face 25 of head 21 and has an under flat pressing face 26 for engagement against the upper face of plate A, when head 21 is lowered.

Shoe 24 is secured to the front sloping face portion of head 23-21 by bolts 27 extending through elongated slots 28 in flanges 29 at each end of shoe 24. By such means, the shoe may be accurately adjusted upwardly or downwardly on the sloping base and there fixedly held by the bolts.

The side pressing shoes 38 are also adjustably mounted on the sloping face 25 by contacting faces 30, and each such shoe has a lower pressing face 31 adapted to be adjusted to the same general plane of face 26 of the middle shoe. For such purpose, the side wall or flange 32 of shoe 38 is longitudinally slotted, as at 33, for the purpose of fixedly holding it to the end faces of head 21 by securing bolt 34. The end of each shoe 38 is provided with a cross flange portion 35, through which extends a bolt hole 36 for adjusting bolt 37, by which each shoe may be accurately set downwardly or upwardly, and then secured by holding bolt 34.

By such means, the outer shoes 38 may be adjusted with relation to the middle shoe 24,

or vice versa, and slight variations in the levels thereof may be purposely made for varying the plane of direct pressure against the plate, dependent upon its tendency at different radial positions to re-act more or less under the flanging action.

As shown in my prior application referred to, the flanging shoe or die f is preferably one of a series of shoes of various depths, and the present invention is capable of application to a machine utilizing such a series of flanging elements or of other construction, as may be desired.

In operation, the reciprocation of the plunger under the action of its supporting head effects downward bending and final flanging of the inner edge portion of plate A, sectionally throughout its perimeter, as sectionally adjusted and operated upon. At each operation, the middle and end shoes 24 and 38 arrive at contacting position with relation to the plate A toward the end of the flanging movement and press steadily downward during the remainder of the stroke, effecting continuous flattening operations clear around the plate, in accompaniment with each flanging movement and the series thereof.

What I claim is:

1. In flanging mechanism, the combination with a supporting base and an upper reciprocable power driven head, of an anvil block, and a pressing head interposed between the anvil block and reciprocable head having a bending face and a plurality of separately adjustable shoes mounted on the pressing head.

2. In flanging mechanism, the combination with a supporting base and an upper reciprocable power driven head, of an anvil block, and a pressing head interposed between the anvil block and reciprocable head having a bending face and provided with a middle adjustable shoe and outermost adjustable shoes mounted on the pressing head.

3. In flanging mechanism, the combination with a supporting base and an upper reciprocable power driven head, of an anvil block, and a pressing head interposed between the anvil block and reciprocable head having a bending face, and an inwardly and downwardly sloping front face, and a middle pressing shoe adjustably secured on said face.

4. In flanging mechanism, the combination with a supporting base and an upper reciprocable power driven head, of an anvil block, and a pressing head interposed between the anvil block and reciprocable head having a bending face and an inwardly and downwardly sloping front face, and a pressing shoe adjustably secured on said face at each side of the pressing head.

5. In flanging mechanism, the combination with a supporting base and an upper

- reciprocable power driven head, of an anvil block, and a pressing head interposed between the anvil block and reciprocable head having a bending face and an inwardly and downwardly sloping front face, a middle pressing shoe adjustably secured on said face, and additional independent pressing shoes adjustably secured on said face at each side of the middle pressing shoe.
- 10 6. The combination with a pressing head of the class described having an inwardly sloping front face, of a middle pressing shoe having slotted flanges and holding bolts extending therethrough for securing the shoe against said face.
- 15 7. The combination with a pressing head of the class described having an inwardly sloping front face, a middle pressing shoe thereon, and flat end faces, of side pressing shoes engaging the sloping face and one end

face, and adjusting and securing bolts therefor.

8. A middle pressing shoe for attachment to the sloping front face of a pressing head as described consisting of an integral block 25 of triangular cross section having a lower contacting face and a smooth attaching face and terminal flanges parallel therewith having bolt engaging slots.

9. A corner pressing shoe for attachment 30 to the sloping corner of a pressing head as described consisting of an integral block having a lower pressing face, a sloping contacting face, a side securing flange having a bolt slot therethrough, and an endmost 35 flange at right angles thereto having a bolt hole.

In testimony whereof I hereunto affix my signature.

JOHN HUBER.
